UNITED STATES PATENT OFFICE.

GEORG SEIBT, OF SCHONEBERG, NEAR BERLIN, GERMANY.

LOUD-SPEAKING TELEPHONE.

Application filed August 1, 1924, Serial No. 729,558, and in Germany August 4, 1923.

This invention relates in general to sound reproducers and more particularly to improvements in loud speaking telephones and especially to telephone receivers comprising a diaphragm of extremely thin and specifically light sheet metal e. g. aluminium sheet of a thickness of .03 mms. and shaped in the form of a curved or conical cup. In consequence of the extremely small mass of such diaphragms the upper harmonics of the same are weakened much less than the harmonics of flat diaphragms. Many attempts have been made to eliminate the disturbing influence of the natural periodic oscillations of such diaphragms, but without success, so that the sounds corresponding to the natural rate of vibration of these diaphragms predominate and the timbre of the sounds to be reproduced is blurred. Thus for example an aluminium diaphragm of the shape illustrated in the drawing of a diameter of 100 mms. and .03 mms. in thickness and carrying an iron armature measuring 12×12×.4 mms. has a pretty distinct natural rate of vibration of 850 per second.

The object of this invention is to improve the faithfulness of the sound reproduction by effectively damping the natural rate of vibration of the diaphragm. This is accomplished by employing similar damping means for the diaphragm of a loud speaking telephone as are used in granular telephonic transmitters i. e. devices in which the diaphragm oscillated by the sound waves exercises a fluctuating pressure in the rhythm of the sound waves on current conducting granules, e. g. carbon granules, placed behind the diaphragm, and thus gives rise to corresponding fluctuations of the electric resistance and consequently to fluctuations of the electric current flowing through the granules. In connection with such telephonic transmitters or microphones it has already been proposed to arrange elastic bodies such as layers of felt or the like behind the diaphragm. These elastic bodies serve as elastic containers for the granules and also as a means for damping the sound oscillations of the diaphragm. In accordance with my invention a light sound-damping material such as light feathers, fluff or down is arranged at the rear of the diaphragm so as to make contact therewith at numerous parts and over the whole surface thereof. The light contact made by the said material with nu-

merous parts of the surface is very effective in damping objectionable vibrations. If the middle of the diaphragm only were to abut upon a sound damping body such as a cushion of felt or soft rubber, the upper harmonics resulting from oscillations of parts of the diaphragm would not be completely suppressed. On the other hand the means I employ result not only in the damping of the fundamental oscillations of the diaphragm but also in the elimination of the metallic timbre that would otherwise be heard. On tapping the middle of a diaphragm arranged according to my invention a sound is produced corresponding to that which is heard when striking against cardboard instead of metal.

For the purpose of explaining the invention two examples embodying the same have been shown in the accompanying drawing, in which the same reference characters have been used in all the views to indicate corresponding parts. In said drawing

Fig. 1, is a sectional elevation showing the apparatus,

Fig. 2, is a similar elevation showing a modification, and

Fig. 3, is a top plan view of Fig. 2.

In the example shown in Fig. 1 the loud speaking telephone comprises a diaphragm *a* in the form of a cup or disk, said diaphragm being made from a sheet of aluminium of a thickness of .03 millimeter. The diaphragm is provided with a flange *b* clamped between the ring *b* of a cylindrical casing *c* and a ring *d*. The diaphragm *a* carries in its centre a small iron armature *e* which is fixed by a small screw *f* and a small dished washer *g*. Fixed to the base *h* of the casing by means of screws *i* and washers *k* is the base plate of an U-shaped electromagnet whose cylindrical pole pieces *l*, which are opposite the iron armature *e*, are surrounded by coils *m* through which the voice currents flow.

The chamber *o* confined by the diaphragm *a*, the cylindrical wall *c* and the bottom *h* of the casing are filled with light feathers such as fluff or down. The damping action thus exercised by the damping agent distributed over the entire surface of the diaphragm results in a talking apparatus or sound reproducer which reproduces the human voice more distinctly and faithfully than has hitherto been possible. The illustrated device is a so-called loud speaker, i. e. a telephone re-

ceiver which is not held to the ear but throws the sound into the surrounding space so as to make it audible to a large number of persons.

5 In Figs. 2 and 3 I have shown a modification in which means are provided for supporting the mass of light material so that it does not bear with its whole weight on the diaphragm, but merely makes contact there-
10 with without exerting material pressure thereon. The general construction of the telephone is the same as has been described with reference to Fig. 1, and the same reference characters have been used to indicate
15 corresponding parts. In the example shown in the figures the supporting means are in the form of a subsidiary diaphragm a^1 dis-
posed at the rear of the main diaphragm a and at a distance of say 2 millimeters there-
20 from and provided with a plurality of holes r distributed over the whole surface of the diaphragm and permitting the feathers or down to make light contact with the main diaphragm a . I have found that thereby a
25 good damping is insured and that the light

material does not bear with its whole mass on the main diaphragm when placing the telephone vertically or with its diaphragm at the bottom side, as might be the case when shipping the telephone. This is important be-
30 cause otherwise the thin diaphragm is sub-
ject to injury even by the light damping mat-
ter.

The supporting diaphragm may be made from sheet metal thicker than .03 millime-
35 ter, say, .1 millimeter.

I claim:—

In a loud speaking telephone, a diaphragm of thin sheet metal, an electromagnet for oscillating the diaphragm, a mass of light material at the rear of the diaphragm, and means to take up the pressure of said ma-
terial towards the diaphragm and permitting the material to make contact with the dia-
phragm and a foraminated plate at the rear
40 of the diaphragm and spaced therefrom and
permitting said material to make contact
through its holes with the diaphragm.
45

In testimony whereof I affix my signature.

DR. GEORG SEIBT.
